HANGER OR SIMILAR ARTICLE

Ruth T. Leach, Mayfield Village, Ohio

Application August 15, 1951, Serial No. 16,286

Term of patent 14 years

(Cl. D33—8)

To all whom it may concern:

Be it known that I, Ruth T. Leach, a citizen of the United States, residing at Mayfield Village, county of Cuyahoga, and State of Ohio, have invented a new, original, and ornamental Design for a Hanger or Similar Article, of which the following is a specification, reference being had to the accompanying drawing, forming a part thereof.

Fig. 1 is a perspective view of a hanger or similar article, showing my new design; and

Fig. 2 is a side elevation thereof.

I claim:

The ornamental design for a hanger or similar article, substantially as shown.

RUTH T. LEACH.
